CLAIM

The ornamental design for a shoe upper as shown and described.

DESCRIPTION

FIG. 1 is a perspective view of a shoe upper in accordance with our new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The dash-dash broken lines shown in the drawings represent environmental structure in the form of a shoe sole as well as portions of the shoe upper that form no part of the claimed design. The dot-dashed broken lines define the bounds of the claimed design and form no part thereof.
